UNITED STATES PATENT OFFICE

JAMES GEORGE WEIR, OF CATHCART, GLASGOW, SCOTLAND, ASSIGNOR TO G. & J. WEIR, LIMITED, OF GLASGOW, SCOTLAND

CLOSED FEED SYSTEM FOR STEAM POWER PLANTS

Application filed August 23, 1927, Serial No. 214,944, and in Great Britain October 8, 1926.

The present invention relates to closed feed systems for steam power plants involving a steam generator, a steam engine (which may be a turbine), a steam condenser, and 5 the necessary steam and feed water connections. It is particularly applicable to steam power plants in which the steam generator is of small water capacity.

The object of the present invention is to 10 provide a simplified arrangement, giving a greater degree of stability and smoothness of working than has been heretofore obtained. The feed tank as ordinarily employed in a closed feed system is dispensed with. (A 15 reserve feed tank is however provided.)

The great objection to a feed tank as ordinarily employed is that, being at atmospheric pressure and open to atmosphere, it gives the feed water an opportunity of taking up air. 20 There may be further disadvantages due to space occupied, weight, and undesirable cooling of the feed water.

According to the present invention there is substituted for the usual feed tank, a well 25 at the bottom of the condenser, the water capacity of this well being sufficiently great to provide the accommodation necessary due to accumulation of feed water in the system caused by changes in the conditions of work- 30 ing of the plant.

Referring to the accompanying drawings:—

Figure 1 illustrates the carrying of the invention into effect in one convenient manner 35 and shows a steam power plant arranged in accordance with the invention.

Figure 2 shows part of a steam power plant to which the invention has been applied: it illustrates a different arrangement of condenser and well from that shown in Figure 1.

Figure 3 shows a steam power plant composed of two units, each of which is a steam power plant as shown in Figure 1.

A well *a*—that is, a space free of tubes—45 is provided at the bottom of the main condenser *b* of the steam power plant shown in Figure 1. A water-extraction pump *c* withdraws the condensate from this well and delivers it to a boiler-feed pump *d* which, in 50 turn, delivers it to the steam generator *e* of

the plant through a valve *f* controlled by a float *g* in the steam generator, which, in the example described, is of the small-water-capacity water-tube type.

The normal water level in the condenser well *a* (that is, the water level under full-power conditions of running the plant) and the capacity of the well are such that the water level may rise to an extent corresponding to the normal fluctuating volume of feed water without flooding the condenser tubes, and may fall to the same extent (as when meeting a sudden demand) without depriving the water-extraction pump of the head of water necessary for its effective operation. 65 In other words, the volume of the well between the maximum and minimum allowable water levels is twice that of the normal fluctuating volume.

In the drawings the normal water level is 70 indicated by the chain-line *x*, and the maximum and minimum allowable water levels by the chain-lines *y* and *z* respectively.

A reserve feed-water tank *h* is provided; 75 and a connection *i* is taken from this tank to the top of the condenser, the connection being provided with a valve *j* controlled by a float *k* in the condenser well *a*. The float *k* acts to close the valve *j* when it rises and to open the valve when it falls. 80

A pipe *m* allows of the supply of water from the discharge of the water-extraction pump *c* to the reserve feed tank *h*, a hand-operated valve *n* being provided for the purpose of controlling the discharge of water 85 to the tank. The tank *h* being under atmospheric pressure and the condenser under a vacuum it will be understood that whenever the valve *j* is opened water is sucked from the tank into the condenser. 90

The reserve feed tank *h* is primarily a tank from which make-up feed water is supplied. When the level in the condenser well *a* is that corresponding to normal (i. e. full-power) conditions of running, as shown by the 95 chain-line *x*, the valve *j* in the connection *i* between this tank and the condenser is arranged to pass only the quantity of water required for make-up feed purposes. When, however, the water level is below the nor- 100

mal, more than this quantity of water is passed by the valve: that is, more water is supplied from the tank h than is required at the moment for make-up feed purposes, with the object of assisting to maintain the water level in the well a within desirable limits.

During normal running of the plant the level of water in the condenser well is substantially constant, and the correct quantity of make-up feed is being admitted to the condenser from the feed tank.

It is a known fact that with a high load on the generator and therefore with a high rate of ebullition, the proportion of steam to water in the water tubes is very great, and the total amount of water in the generator is very small with respect to the steam generated per hour. Therefore, the reduction of the amount of water in the water tubes when the generator is steaming at a high rate has a distinct influence on the amount of water in the steam and water drum of the generator, that is, the drum in which, according to the present invention, the float g is placed. Therefore, for the same amount of water in the generator e the float g is higher with a high rate of steam generation therein with a low rate, that is, it is higher with a load than with a low load.

Consequently, if the load on the steam generator e suddenly drops, the water level in it drops due to the consequent reduction in ebullition. The float-controlled valve f in the steam generator e throttling the discharge of the feed pump d which is of the centrifugal type will then act to cause the feed pump d to supply more water from the condenser well a and thus to bring up the water-level in the generator. By virtue of the provision of a condenser well as described this sudden demand for water can be met without leading to the water-extraction pump being left with an insufficient suction head.

When the plant resumes normal running after having been running under manoeuvring or standby conditions for some time, water in excess of the normal full-power steaming quantity will have accumulated in the feed system. This is brought about by a reduction in ebullition when the load drops, and the bringing up of the generator water level by water from the condenser well, as just described. While the condenser well level is below the normal, the valve j on the feed tank connection i will be passing more water than is required for make-up; the level in the well will therefore rise, and, if standby conditions continue, the well level will eventually be brought up to normal. The generator water-level will now be at normal also. When the plant resumes normal working, the generator water level will rise above normal, due to the increase in ebullition for the reason hereinbefore specified, and the generator float-controlled valve

f will act to reduce the quantity of water supplied by the feed pump d . Water will therefore then accumulate in the condenser well and, as pointed out above, the well is made sufficiently large to allow of this accumulation without leading to flooding of the condenser tubes.

It will be seen that there is no feed tank as ordinarily provided in a closed feed system. Considerable economy in space is therefore attained, a feature which is of great importance in warships. The provision of a large well at the bottom of the condenser is generally of no disadvantage as regards space provision, the necessary space usually being so available.

When the invention is applied to existing installations, a well or tank a is provided and is placed, as shown in Figure 2, so as to allow water to gravitate into it from the condenser b : it is connected to the condenser by a water-delivery pipe o . This well or tank a takes the place of the well a described above with reference to Figure 1. This arrangement functions in precisely the same manner as that just described.

The invention may be applied to a steam power plant comprising two units working in parallel as shown in Figure 3. Each unit includes a steam generator, steam condenser, and boiler-feed and water-extraction pumps, together with the necessary steam and feed-water connections. The condenser b of each unit is provided with a well a as described above, with reference to Figure 1. Water may be supplied to each condenser from a common reserve feed tank h , the supply of water to each condenser being controlled by a valve j actuated by a float k in the well of that condenser. Provision is made for supplying water to the common feed tank from the discharge of the water-extraction pump of either unit.

The feed water main of one unit is connected to that of the other unit by means of cross pipes p and s , each provided with a valve r and t respectively. The pipe p is interposed between the water extraction and boiler feed pumps c and d while the pipe s is positioned between the condensers b and the water extraction pumps c . With such an arrangement when the water level in the condenser of one unit is higher than that in the condenser of the other unit, water will be transferred from one unit to the other upon opening of the valves in the cross pipes, owing to the difference in the head of the suction sides of the respective water extraction pumps. In practice, if desired, it will be understood that either one of the pipes p or s , may be eliminated, leaving the remaining pipe to establish equalization of water level in the different units.

Having thus described my invention, what

I claim as new and desire to secure by Letters Patent is:—

5. A steam power plant working on a closed feed system and consisting of a plurality of units—each including a steam generator, a steam engine operated by the steam generated in said steam generator, a steam condenser for said engine, a water main for returning steam condensate from the condenser to the generator, and a water extraction pump and a boiler feed pump in said main, there being a well at the bottom of each of said condensers so placed that the condensate obtained from the condensation of 10 steam in said condenser gravitates into it, the water capacity of this well being sufficiently great to provide the accommodation necessary due to accumulation of feed water in the unit caused by changes in the conditions of working of the plant—a pipe connecting together the feed water mains of the several units between said condenser and said boiler feed pump in each case, and a valve on the pipe in each case.

25 2. A steam power plant working on a closed feed system and consisting of a plurality of units—each including a steam generator, a steam engine operated by the steam generated in said steam generator, a steam condenser for said engine, a water main for returning steam condensate from the condenser to the generator, and a water extraction pump and a boiler feed pump in said main, there being a well at the bottom of each 30 of said condensers so placed that the condensate obtained from the condensation of steam in said condenser gravitates into it, the water capacity of this well being sufficiently great to provide the accommodation necessary due to accumulation of feed 35 water in the unit caused by changes in the conditions of working of the plant—pipes connecting together the feed water mains of the several units between said condenser and 40 said boiler feed pump in each case, and a valve on each of said pipes.

3. A steam power plant working on a closed feed system and consisting of a plurality of units—each including a steam generator, a steam engine operated by the steam generated in said steam generator, a steam condenser for said engine, a water main for returning steam condensate from the condenser to the generator, and a water extraction pump and a boiler feed pump in said main, there being a well at the bottom of each of said condensers so placed that the condensate obtained from the condensation of steam in said condenser gravitates into it, the water capacity of this well being sufficiently great to provide the accommodation necessary due to accumulation of feed water in the unit caused by changes in the conditions of working of the plant—a pipe connecting together the feed water mains of

the several units on the discharge sides of said water-extraction pumps, and a valve on the pipe in each case.

4. A steam power plant working on a closed feed system and consisting of a plurality of units—each including a steam generator, a steam engine operated by the steam generated in said steam generator, a steam condenser for said engine, a water main for returning steam condensate from the condenser to the generator, and a water extraction pump and a boiler feed pump in said main, there being a well at the bottom of each of said condensers so placed that the condensate obtained from the condensation of steam in said condenser gravitates into it, the water capacity of this well being sufficiently great to provide the accommodation necessary due to accumulation of feed water in the unit caused by changes in the conditions of working of the plant—pipes connecting together the feed water mains of the several units on the discharge sides of said water-extraction pumps, and a valve on each of said pipes.

5. A steam power plant working on a closed feed system and consisting of a plurality of units—each including a steam generator, a steam engine operated by the steam generated in said steam generator, a steam condenser for said engine, a water main for returning steam condensate from the condenser to the generator, and a water extraction pump and a boiler feed pump in said main, there being a well at the bottom of each of said condensers so placed that the condensate obtained from the condensation of steam in said condenser gravitates into it, the water capacity of this well being sufficiently great to provide the accommodation necessary due to accumulation of feed water in the unit caused by changes in the conditions of working of the plant—a pipe connecting together the feed water mains of the several units between said condenser and said boiler feed pump in each case, and a valve on the pipe in each case, a reserve feed tank, a connection from said tank to each of said condensers, and a valve on each of said connections.

6. A steam power plant working on a closed feed system and consisting of a plurality of units—each including a steam generator, a steam engine operated by the steam generated in said steam generator, a steam condenser for said engine, a water main for returning steam condensate from the condenser to the generator, and a water extraction pump and a boiler feed pump in said main, there being a well at the bottom of each of said condensers so placed that the condensate obtained from the condensation of steam in said condenser gravitates into it, the water capacity of this well being sufficiently great to provide the accommoda- 120

tion necessary due to accumulation of feed water in the unit caused by changes in the conditions of working of the plant—pipes connecting together the feed water mains of the several units between said condenser and said boiler feed pump in each case, and a valve on each of said pipes, a reserve feed tank, a connection from said tank to each of said condensers, and a valve on each of said connections.

7. A steam power plant working on a closed feed system and consisting of a plurality of units—each including a steam generator, a steam engine operated by the steam generated in said steam generator, a steam condenser for said engine, a water main for returning steam condensate from the condenser to the generator, and a water extraction pump and a boiler feed pump in said main, there being a well at the bottom of each of said condensers so placed that the condensate obtained from the condensation of steam in said condenser gravitates into it, the water capacity of this well being sufficiently great to provide the accommodation necessary due to accumulation of feed water in the unit caused by changes in the conditions of working of the plant—a pipe connecting together the feed water mains of the several units between said condenser and said boiler feed pump in each case, and a valve on the pipe in each case, a reserve feed tank, a connection from said tank to each of said condensers, a valve on each of said connections, connections between said feed water mains and said reserve feed tank, and a valve on each of said last-mentioned connections.

8. A steam power plant working on a closed feed system and consisting of a plurality of units—each including a steam generator, a steam engine operated by the steam generated in said steam generator, a steam condenser for said engine, a water main for returning steam condensate from the condenser to the generator, and a water extraction pump and a boiler feed pump in said main, there being a well at the bottom of each of said condensers so placed that the condensate obtained from the condensation of steam in said condenser gravitates into it, the water capacity of this well being sufficiently great to provide the accommodation necessary due to accumulation of feed water in the unit caused by changes in the conditions of working of the plant—pipes connecting together the feed water mains of the several units between said condenser and said boiler feed pump in each case, and a valve on each of said pipes, a reserve feed tank, a connection from said tank to each of said condensers, a float in each of said wells, and a valve on each of said connections, each of said valves being controlled by the float in the corresponding condenser.

9. A steam power plant working on a

closed feed system and consisting of a plurality of units—each including a steam generator, a steam engine operated by the steam generated in said steam generator, a steam condenser for said engine, a water main for returning steam condensate from the condenser to the generator, and a water extraction pump and a boiler feed pump in said main, there being a well at the bottom of each of said condensers so placed that the condensate obtained from the condensation of steam in said condenser gravitates into it, the water capacity of this well being sufficiently great to provide the accommodation necessary due to accumulation of feed water in the unit caused by changes in the conditions of working of the plant—a pipe connecting together the feed water mains of the several units between said condenser and said boiler feed pump in each case, and a valve on the pipe in each case, a reserve feed tank, a connection from said tank to each of said condensers, a valve on each of said connections, connections between said feed water mains and said reserve feed tank, and a valve on each of said last-mentioned connections.

10. A steam power plant working on a closed feed system and consisting of a plurality of units—each including a steam generator, a steam engine operated by the steam generated in said steam generator, a steam condenser for said engine, a water main for returning steam condensate from the condenser to the generator, and a water extraction pump and a boiler feed pump in said main, there being a well at the bottom of each of said condensers so placed that the condensate obtained from the condensation of steam in said condenser gravitates into it, the water capacity of this well being sufficiently great to provide the accommodation necessary due to accumulation of feed water in the unit caused by changes in the conditions of working of the plant—pipes connecting together the feed water mains of the several units between said condenser and said boiler feed pump in each case, and a valve on each of said pipes, a reserve feed tank, a connection from said tank to each of said condensers, a valve on each of said connections, connections between said feed water mains and said reserve feed tank and a valve on each of said last-mentioned connections.

I hereby sign my name to this specification.

JAMES GEORGE WEIR.
